DESIGN FOR A DESK LAMP

Clarence L. Dewey, Elkhart, Ind.

Application July 6, 1942, Serial No. 107,436

Term of patent 14 years

To all whom it may concern:

Be it known that I, Clarence L. Dewey, a citizen of the United States and resident of Elkhart, county of Elkhart, and State of Indiana, have invented a new, original, and ornamental Design for a Desk Lamp, of which the following is a specification, reference being had to the accompanying drawing, forming a part thereof, wherein:

Fig. 1 is a perspective view of a desk lamp showing my new design, and

Fig. 2 is a sectional view taken on line 2—2 of Fig. 1.

The dominant feature of my design is shown in full black lines in the drawing.

I claim:

The ornamental design for a desk lamp, substantially as shown and described.

CLARENCE L. DEWEY.
